Reiter & Schumacher

UNITED STATES PATENT OFFICE

HERMAN LEVEY, OF BROOKLYN, NEW YORK

SHIRT-DISPLAY CARD

Application filed October 6, 1928. Serial No. 310,693.

This invention relates to shirt cards and has among its objects the provision of an improved device of the nature set forth which displays a shirt smoothly and evenly.

5 Another object of the invention is to provide an improved device of the character described, having a reenforced edge that permits a shirt to be drawn taut over the card, and to show an even, and uniform appearance.

10 A further object of the invention is to construct a device of the type mentioned that has an improved feature permitting the shirt to be attached to the card by means of pins, the points whereof are protectively retained 15 within the card, the pins being engaged with the card in a simplified manner.

Other objects and advantages of the invention will become apparent as the specification proceeds.

20 With the aforesaid objects in view, the invention consists in the novel combinations and arrangements of parts hereinafter described in their preferred embodiments, pointed out in the subjoined claims, and illustrated on the 25 annexed drawing, wherein like parts are designated by the same reference characters throughout the several views.

In the drawings:

Figure 1 is a view of a device embodying 30 the invention, and showing a shirt mounted thereon.

Fig. 2 is a rear view in elevation of the shirt card.

Fig. 3 is a side edge view of the same 35 mounted on a pedestal.

Fig. 4 is a rear view of the arrangement shown in Fig. 3.

Fig. 5 is an enlarged sectional view taken 40 on line 5—5 of Fig. 2.

Fig. 6 is a fragmentary sectional view taken 45 on line 6—6 of Fig. 2.

The advantages of the invention as here outlined are best realized when all of its features and instrumentalities are combined in 45 one and the same structure, but, useful devices may be produced embodying less than the whole.

It will be obvious to those skilled in the art to which the invention appertains, that 50 the same may be incorporated in several dif-

ferent constructions. The accompanying drawing, therefore, is submitted merely as showing the preferred exemplification of the invention.

Generally described, the invention provides 55 an improved shirt card, which is plane and of sufficiently stiff character to permit a shirt to be tightly stretched thereover for display mounting in a store window or the like. For this purpose it is desirable that the cards be 60 of a uniform and predetermined nature so that all the shirt display may appear neat and attractive. On the one hand the elimination of the "home" cutting of cards is desirable, and likewise the annoyance of cards of the 65 wrong size, and on the other hand it is found desirable to improve the appearance of the store window and to save considerable time and labor where all the cards are made according to a predetermined plan for uniformity 70 in size and shape. Thus no trimming of the cards is necessary. Furthermore, on my improved card, a shirt can be set up with a minimum number of pins. While the card is 75 made of any suitable, inexpensive material, that possesses sufficient stiffness and body, as for example, cardboard, the edges of the latter are reenforced with any material that sufficiently strengthens the edges of the card to permit the shirt to be drawn tight 80 over said edges, and also to cause the shirt edges so formed to appear smooth and straight.

The reenforcing material may clearly vary 85 with the material used for the body of the card, and where the latter is formed of corrugated cardboard the reenforcement preferably consists of a metal strip of V-form that extends along the edges of the card, and binds 90 the same snugly, thoroughly concealing the corrugations at the edges of the card, and compressing the same down to a thin edge. The corrugations permit pins to be easily inserted 95 at an angle into the card, with the points of the pins protectively retained within the card. The metal reenforcement consists of a very thin metal so as to have no appreciable weight. The cardboard forms a backing for the metal to hold the latter rigid and in proper 100 shape.

It will be apparent that while the device is shown in conjunction with shirts, that it is equally applicable to articles of various kinds, that are made of a fabric, or other pliable material and which articles have to be stretched and retained taut for display or other purposes.

Referring in detail to the drawing, 10 denotes a device embodying the invention. The 10 same includes a shirt card C upon which is mounted a shirt S. The latter is folded over the shirt card in the usual manner well known for display purposes to show to the maximum advantage, the front of the shirt, including the collar and cuffs. The sides and bottom 15 of the shirt, and the major part of the sleeves are concealed at the rear of the shirt card. Attention is particularly directed to the neat side and bottom edges 11 and 12 of the device 10.

The shirt card includes a single ply of corrugated board 13, consisting of the usual outer layers of paper 14 between which is disposed the corrugated filler 15. Binding 25 all four edges of the body 13 are metallic strip members 16 and 17 which are of V-form in cross section. These constitute a reenforcement for the cardboard, and provide an absolutely smooth, straight edge. The members 16 and 17 clamp the edge portions of the cardboard so as to reliably engage the same, and also to form a thin edge for the display card C. At the corners of the latter, finishing members 18 are provided to cover 30 the edges of the metallic reenforcing strips. The members 18 may consist of paper or fabric pasted around the corners of the display card. The said metallic strips may be rendered rust-proof by painting, enameling, 35 or the like. As thus constructed all parts of the display card are of uniform character. The metal strips 16 and 17 are as thin as possible for lightness. They do not possess sufficient strength in themselves to support 40 the shirt in proper form, but are backed up by the cardboard. The latter of course facilitates the handling of the device and the folding of the shirt thereon.

At one end of the display is fastened a 45 supporting member 19 for the device C, said member being of flexible metal of loop form, riveted in place at 20. One manner of using the supporting member is as shown in Fig. 3, where the same is bent over an arm 21 of a 50 pedestal 22. In this position, the display card holds a shirt in inclined relation.

The shirt S is secured to the display card C by pins 23 of any conventional type, preferably straight. No more than six pins are 60 needed to set up a shirt. The pins are inserted into the corrugated board at an angle, and since the material 15 is soft, entrance of the pin is easily effected. The points 24 of the pins are protectively retained between the 65 plies 14 of the corrugated board. It will be

clearly apparent that the tension of the shirt on the pins is such as to take advantage of the direction of inclination of the latter to prevent the pins from being loosened. The pins may be so placed that the heads thereof are concealed.

I claim:

1. A shirt display card comprising a corrugated cardboard having substantially straight edges, and a thin metallic strip 75 embracing said edges, said strip being of V cross section forming thin, smooth edges for the cardboard at the apex of the V, the said metallic strip lying substantially entirely between the planes of the opposite faces of the 80 cardboard.

2. A shirt display card comprising a corrugated cardboard having substantially straight edges, and a thin metallic strip along 85 said edges, the said edges of the corrugated board being crushed thin, and the said strip enclosing the said edges forming a thin smooth edge for the device.

3. A shirt display card comprising a corrugated cardboard having substantially straight edges over which a shirt may be 90 folded, drawn tight and pinned in position, and pins for the shirt extending substantially through the corrugated board in straight lines and retained by the cardboard in pre-determined position and direction through the same.

In testimony whereof I affix my signature.
HERMAN LEVEY.
